ELECTRONIC CONTROL FOR ELECTRICALLY
OPERATED DEVICES

Walter P. Menkhaus, Philadelphia, Pa.

Application January 23, 1948, Serial No. 3,888

6 Claims. (Cl. 171—97)

1

The object of the invention is to provide improvements in electronic controls or interrupters especially designed for the operation of intermittent electric signs, beacons, traffic control signals and in fact every conceivable electrically controlled device or mechanism, that is intended to be alternately energized or actuated in periodic sequence, this application covering an improvement over the disclosure of copending application Serial No. 718,863, filed December 27, 1946.

More particularly, an object of the invention is to provide a control of this type, which possesses a combination of functions, one of which is to control the operation of intermittent test apparatus, flash signs such as are used for advertising, warning and similar purposes characterized by periods of energizing and deenergizing two different circuits whether of the same or different duration, while the other function is to simultaneously, yet independently of the first, operate a progressive set of circuits such as the minimum of three groups of lamps in a border that when energized in a predetermined sequence create appearance of a travelling or progressive effect, such for example as a scintillating or rippling border of a sign.

A further object is to provide a completely automatic device of this class, which wholly eliminates the necessity heretofore of employing a motor and commutator combination, which are usually limited to a single predetermined periodic control, such as can be altered only by changing the design of the commutator and/or the speed of the motor.

And a still further object is to provide a device of this character, which experiences but little depreciation through wear and tear, and in which substantially the only replacement involved is when the tubes burn out or a relay contact requires cleaning, and such similarly relatively insignificant details.

Reference to the accompanying wiring diagram indicates better than a detailed description how the several elements are inter-connected, each of said elements being identified by standard nomenclature, while three of the variable resistances are shown as being connected by relatively heavy broken lines, to indicate that they are preferably oscillated angularly in unison, as by means of a single dial.

In the operation of the invention as represented by the embodiment shown in the drawings, the plug 1 is connected to any suitable source of alternating current, but usually to a source

2

delivering about 110-120 volts which is widely standard. The switch 2 is closed, thereby energizing the primary of the transformer 3 and causing current from the smaller undivided transformer secondary 3b to energize the filaments of the tubes 21, 38 and 51 at full voltage and of tube 4 at a lower voltage, due to the action of the resistor 5, which is between the tube 4 and said transformer secondary. This prevents tube 4 from reaching operating temperature until after tubes 21, 38 and 51 have reached their proper temperatures and are ready to function. At the same time bias voltage from the larger transformer secondary 3a is applied to the control grid of tube 21 through resistors 6 and 14, to the control grid of tube 38 through resistors 24 and 25, and the control grid of tube 51 through resistor 42. This voltage is 180° out of phase with the plate voltage of said tubes 21, 38 and 51, said plate voltage being supplied to tube 21 through relay coil 26, tube 38 through relay coil 29, and to tube 51 through relay coil 44, said plate voltage being supplied to tubes as long as power is supplied to device, whether tubes are conducting or not conducting.

Since the control grids of said tubes 21, 38 and 51 are negative with respect to the cathodes of said tubes when their plates are positive with respect to the cathodes of said tubes, the tubes can not pass current through their respective relay coils, and the coils consequently remain de-energized. Current, however, can flow through tube 4, relay contact 13, variable resistor 7 and into condenser 8, permitting a positive charge to build up in said condenser, the duration of the charging time being dependent upon the setting of variable resistor 7. This positive charge is applied to the control grid of tube 21 through resistor 15, and when the magnitude of this positive charge or voltage is sufficient to cancel out, or offset, the negative voltage being applied to the grid of said tube through resistors 6 and 14, the tube passes current from its cathode to its plate, said current flowing through the relay coil 26 and energizing the relay, which operates to change the setting of its respective contacts. During the period thus described, the portion of the sign or other device being controlled through its connection to output receptacle 16 was receiving no current, due to its relay contact 9 being open, while that portion of the sign or the like being controlled through its connection to output receptacle 17 was receiving current for its operation due to said relay contact 10 being closed.

When tube 21 passes current through relay coil 26, causing it to operate that portion of the sign connected to outlet 16, said sign receives current due to closing of contact 9, while the other portion of the sign connected to outlet 17 receives no current, due to the opening of the contact 10, at the same time relay contacts 11 and 12 close and relay contact 13 opens. The opening of contact 13 arrests the flow of current to said condenser 8, which current it had received from tube 4, and permits the positive charge in said condenser to leak off through contact 12 (now closed), fixed resistor 19 and variable resistor 20. The duration of time required for the charge to leak off depends upon the setting of the variable resistor 20. At the same time closing of contact 11 has connected resistance 18 in series with resistance 6 and reduced the negative voltage applied to the control grid of tube 21 through resistance 14. When the positive voltage delivered from condenser 8 through resistor 15 reaches a point where it is less than the negative voltage applied through resistance 14, the grid of tube 21 will again be negative with respect to its cathode, and the tube will stop "firing" or passing current from its cathode to its plate, and the relay coil will become deenergized. This will restore the contacts to their original positions and the cycle of operation will be repeated. This arrangement provides two outlets 16 and 17, which accordingly deliver current consecutively or alternately, the time duration of either of which can be separately controlled.

During the cycle of operation just described, and independently thereof, current has been flowing from tube 4, through relay contact 35, variable resistor 28 and condenser 39, permitting a positive charge to build up in condenser 39, the duration of the charging time depending upon the setting of the variable resistor 28. This positive charge is applied to the control grid of tube 38 through the resistor 27, and when the magnitude of this positive charge or voltage is sufficient to cancel out, or offset, the negative voltage being applied to the grid of said tube through resistors 24 and 25, the tube passes current from its cathode to its plate, the current flowing through the relay coil 29 and energizing the relay, which thereby operates to change the setting of its respective contacts. During this period, that portion of the sign or the like connected to the outlet receptacle 48 has been receiving current for its operation through contact 31 which has been closed. At the same time, those portions of the sign connected to outlet receptacles 49 and 50 have been receiving no current, due to contacts 45 and 30 being open. Also, at the time of energizing the relay coil 29, contacts 32 and 35 open and contacts 33 and 34 close.

Opening of contact 35 arrests the flow of current from tube 4 through variable resistor 28 and condenser 39. This stops the accumulation of a positive charge in condenser 39. The closing of contact 33 connects resistor 36 in series with resistor 24 and lowers the negative voltage applied to the control grid of tube 38 through resistor 25. The closing of contact 34 permits current to flow from tube 4 through variable resistor 40 and condenser 41, permitting a positive charge to accumulate in condenser 41, the duration of the charging time depending upon the setting of variable resistor 40. This charge is applied to the control grid of tube 51 through resistor 43, and when the magnitude of said

charge or voltage is sufficient to cancel out or offset the negative voltage being applied to the control grid of said tube through resistor 42, the tube passes current from its cathode to its plate, said current flowing through relay coil 44 and energizing the relay, which operates to change the setting of its several contacts.

During the period just covered, that portion of the sign connected to outlet receptacle 50 has been receiving current through contacts 46 and 30, which have been closed. At the same time, that portion of the sign connected to outlets 48 and 49 have been receiving no current, due to contacts 31 and 45 being open. Likewise, tube 38 has been firing or passing current continuously during the same period. At the time of energizing relay coil 44, contact 41 closes and connects variable resistor 53 in parallel with condenser 39. This permits the positive charge or voltage in condenser 39 to leak off and the magnitude of the voltage applied to the control grid of tube 38 through resistor 27 decreases and will in a given time, depending upon the setting of the variable resistor 53, reach a point where it becomes less than the negative voltage applied through resistor 25, and when this condition is reached the tube's grid again becomes negative, and it ceases to pass current. This restores the contacts 30, 31, 32, 33, 34 and 35 to their original positions.

The return of contact 32 to its original position places resistor 23 in parallel with condenser 41, discharging it rapidly so that the positive charge across it is no longer applied to the control grid of tube 51 through resistor 43, and said grid thereupon becomes negative with respect to its cathode due to the negative voltage being applied through resistor 42, causing the tube to stop passing current through relay coil 44, and contacts 45, 46 and 47 are at the same time restored to their original positions. During this period, that portion of the sign or the like connected to outlet 49 has been receiving current for its operation as the result of contacts 45 and 30 having been closed, while portions of the sign connected to outlets 50 and 48 have been receiving no current, due to contacts 46 and 31 being open. Also, at the end of this period, the contacts of both relays have been restored to their original settings and the cycle of operation is repeated.

This wiring arrangement provides the three outlets 48, 49 and 50, which from their positions in the circuit permit the connection thereto of the same number of lamps (or other elements or groups of elements intended to operate in sequence), with the result that these last-mentioned lamps or elements whether single or in multiple recurrent arrangement as in a border, will be illuminated in one, two, three sequences for as long as may be desired. The duration of each energizing or illumination may be either relatively instantaneous or for a more prolonged period, but if of relatively short duration the effect in a border will be to make said border appear to "travel" continuously in one direction, either fast or slow. The period of illumination can be controlled either simultaneously by coupling the three variable resistor 28, 40 and 53 together, as indicated by the dotted lines, or independently of one another if preferred, thus making a form of start-and-stop, or fast-and-slow motion to the apparent progress of the border or the like.

From the foregoing it will be apparent that, an electronic control of simple adjustability and

operation has been provided, and that the values given are purely representative of what can be effected without changing the general assembly of the several elements, such as the condensers, tubes, resistances, relays, etc., while it is recognized that at this time the principles of internal electric operation may not be fully understood.

Condensers 22, 37 and 52 are not essential to operation of the control, but are present and used in order to prevent the emission of radio frequency waves, having a step wave front, which would otherwise be likely to cause interference (so-called man-made static) in radio receivers located in the immediate vicinity of the control. Consequently, these last-mentioned condensers may be omitted without interfering with the operation of the control, as it performs its intended functions.

When variable resistances 28, 40, and 53 are connected together mechanically for simultaneous operation, it may be necessary to connect one or more additional resistors, not shown, in parallel or across one or more of said variable resistances to equalize the time of which current or power is delivered to channels 48, 49 and 50, due to variations in values of various parts used.

In the specification and claims, the terms firing, passing current, or conducting, when referring to a thyratron means that the thyratron is passing current from its cathode to its plate on the positive half of the plate voltage cycle and not firing, stops firing, or not conducting, means that the thyratron is not passing current from its cathode to its plate on the positive half of the plate voltage cycle. The name "Thyratron" refers to a grid-controlled rectifier tube of the mercury vapor vacuum type.

Having thus described my invention, what I claim and desire to protect by Letters Patent of the United States is:

1. An electronic control for controlling electrically operated devices, comprising a rectifier tube and three thyratron, grid-controlled rectifier tubes, a potential transformer having a primary and two secondaries one of which is split, said primary being connected to a source of alternating current, the filaments of said tubes being heated from the misplit secondary, the tape of the split secondary being connected to one side of the current source and to the cathode of each of the said three thyratron tubes, said cathodes being also connected to the suppressor grids of said tubes, one side of said split secondary being connected to the plate of said rectifier tube while the other side of said split secondary is connected to the grid of said thyratron tubes through resistances, three relays connected to said current source and actuated by the respective thyratron tubes, each of said relays having normally open and normally closed contacts for controlling current discharge terminals, a condenser connected through a variable resistance and a normally closed contact of one of said relays to the cathode of said rectifier tube, said condenser also being connected to one of said thyratron tubes through a resistance, said condenser also being connected through a second normally open relay contact and through a fixed resistor and a variable resistor to the cathode of said last-mentioned thyratron tube, a third normally open contact of said relay being connected between the cathode of said last-mentioned thyratron tube, a resistance and the end of said split transformer secondary, the other side of said condenser being connected to the cathode of said last-mentioned thyratron tube, a

second condenser connected through a variable resistance and normally closed contact on a second relay to the cathode of said rectifier tube, said last-mentioned condenser also being connected to a second thyratron tube through a resistance, and said last-mentioned condenser also being connected through a normally open contact of the third relay and a variable resistance to the cathode of said second thyratron tube, a second normally open contact on said second relay being connected between the cathode of said second thyratron tube, a resistance and the end of said split transformer secondary, while the other side of said second condenser is connected to the cathode of said second thyratron tube, a third condenser connected through a variable resistance and a normally open contact on said second relay to the cathode of said rectified tube, said last-mentioned condenser also being connected to the third thyratron tube through a resistance, said last-mentioned condenser also being connected through a normally closed contact on the second relay to the cathode of said third thyratron tube.

2. A device constructed in accordance with claim 1, in which altering of at least one variable resistor varies the length of time current is applied to one pair of said terminals, and variation of three of the remaining variable resistors varies the length of time which current is applied in sequence to the corresponding three pairs of said terminals independently of said first-mentioned pair of terminals.

3. In a device of the class described, the combination of a thyratron tube, means to supply current thereto, electrical means by which the opening and closing of the contacts of a relay in the plate circuit causes changes in the voltages applied to the control grid of said tube, thereby causing said tube to start and stop conducting alternately and continuously as long as power is applied to the device, control means whereby the length of time the tube is conducting or not conducting can be regulated independently, and means whereby power can be delivered to output terminals alternately and continuously for the identical length of time as the said tube is conducting or not conducting current.

4. A device according to claim 3, wherein power means are provided for a thyratron having its cathode connected to one side of the power source and its plate connected to the opposite side of said source through a relay coil, and wherein means are provided whereby the opening and closing of the contacts of the relay changes the voltages applied to the control grid of said tube causing said tube to become conductive and non-conductive alternately and continuously, and means to control the periods of conduction and non-conduction of said tube.

5. A device of the class described, wherein first and second thyratron tubes are connected so that the opening and closing of contacts of a relay in the plate circuit of one of said tubes causes changes in the voltages applied to the control grid of the second of said tubes, to cause said second tube to start and stop conducting, which through the opening and closing of contacts of a relay in the plate circuit of said second tube causes changes in the voltage applied to the control grid of said first tube, thereby causing it to start and stop conducting, said tubes starting and stopping conduction alternately and continuously as long as power is applied to the device, means whereby power can be delivered to the output terminals alternately and continuously for the

70
75

identical length of time as said tubes are conducting or not conducting, and means whereby the length of time said tubes are conducting or not conducting can be controlled independently or simultaneously with each other.

6. A device according to claim 5, wherein all of the cathodes of the said tubes are connected directly to one side of the power source and all of the plates of said tubes are connected through their respective relay coils to the other side of said power source, and wherein the contacts on said relays by being opened and closed by the

operation of the relay by the thyratron changes the voltages applied to the control grids of said tubes, causing said tubes to start and stop conducting, the starting and stopping of the conduction being alternate and continuous, means whereby the relay can control its own thyratron or another succeeding thyratron tube, and means whereby the length of the periods of conduction and non-conduction can be controlled independently of or simultaneously with one another.
